IMPROVEMENT IN CHURNS.

A. J. POPE, OF STRONGSVILLE, OHIO.

Letters Patent No. 60,240, dated December 4, 1866.

SPECIFICATION.

TO ALL WHOM IT MAY CONCERN:

Be it known that I, A. J. POPE, of Strongsville, in the county of Cuyahoga, and State of Ohio, have invented certain new and useful improvements in Churns; and I do hereby declare that the following is a full and complete description thereof, reference being had to the accompanying drawings, making a part of this specification, in which—

Figure 1 is a perspective view.

Figure 2 is a vertical section.

Like letters of reference refer to like parts in the different views presented.

In the drawings, A represents the case, which is in form an oblong square. This case is supported on the legs, B, which extend to the top of the case as shown, the sides of which are connected and held firmly together by means of the rods, *a*, extending from the side, being secured by means of nuts, *a'*, the under side or bottom of the churn being curved, as shown in fig. 2, to coincide with the sweep of the dashers. C C are standards connected one to each side of the case. These extend up, as shown, being bent until they meet above the churn, and the ends are connected by means of the link *c*. These standards are for the purpose of attaching the pendulum, to which the handle is secured. D is the pendulum, the end of which is held between the ends of the standards, C, a pin, *b*, passing through them and holding them in place. To the lower end of the pendulum is secured the handle E, which extends from one end of the churn to the other, and is provided with a gib and key at *d*, for the purpose of disjointing it at each end, so that it will require less room. F F are arms, which are attached to and extend down from the handle E, through the cover, into the case of the churn. The cover or lid, A', is in two parts or sections, which is removed, one section at each end. Through the centre of the cover is a slot through which the arms pass, a narrow strip, *e*, being placed over this slot to prevent the cream from being thrown out by the action of the dashers. B' is a piece or strip for the purpose of holding the standards C in place and preventing them from being pulled or thrown down sideways. Under this piece is placed the beater, G, which is composed of several upright strips or bars, secured to the top piece, G'. This beater can be easily removed from the churn when desired. To the arms F, above referred to, are connected the dashers, H. These consist of the pieces I, from which extend out the ribs I'; the piece I being perforated between said ribs, as indicated by fig. 2.

When the churn is in operation the end of the handle is forced down, thus raising the other, which brings the dashers in contact with the beater, as indicated by the dotted lines in fig. 2; and the handle being raised, lowers the other end, each working and bringing each dasher alternately in contact with the beater G. In this way the cream is greatly agitated and the churn operated without trouble or much labor. A machine constructed in this way on a large scale can be used for washing clothes, while one constructed on the same principle, only smaller, will be used for a churn.

What I claim as my invention, and desire to secure by Letters Patent, is—

The standard C, pendulum D, and handle E, in combination with the arms F, dasher H, and beater G, constructed and operated as and for the purpose set forth.

A. J. POPE.
